DESIGN FOR A CLOCK

Jim I. Silvers, Chicago, Ill.

Application October 6, 1938, Serial No. 80,289

Term of patent 3½ years

To all whom it may concern:

Be it known that I, Jim I. Silvers, a citizen of the United States, residing at Chicago, in the county of Cook and State of Illinois, have invented a new, original, and ornamental Design for a Clock, of which the following is a specification, reference being had to the accompanying drawing, forming part thereof.

In the drawing:

Fig. 1 is a front elevation of a clock showing my new design.

Fig. 2 is a side elevation of the same.

Fig. 3 is a top plan view of the same.

I claim:

The ornamental design for a clock, as shown.

JIM I. SILVERS.
